UNITED STATES PATENT OFFICE.

GEORGE A. WHITE, OF BOSTON, MASSACHUSETTS.

HEEL LIFT AND TAP.

SPECIFICATION forming part of Letters Patent No. 283,048, dated August 14, 1883.

Application filed January 15, 1883. (No model.)

To all whom it may concern:

Be it known that I, GEORGE A. WHITE, a citizen of the United States, residing at Boston, in the county of Suffolk and State of Massachusetts, have invented certain new and useful Improvements in Cutting Heel Lifts and Taps; and I do hereby declare that the same are fully described in the following specification and illustrated in the accompanying drawings.

This invention relates to improvements in cutting and making heel lifts and taps, as well as rands and welts for boots and shoes; and it has for its object the utilization of comparatively small pieces of leather for making heel-lifts and what are termed "slip-taps," in such a manner as to produce a continuous and unbroken exterior edge, without any unsightly seams, which are so common in ordinary pieced 20 heels and slip-taps for boots and shoes.

In carrying out my invention I use a die, which will be subject-matter for a separate application for Letters Patent, and with the said die I cut out a piece of leather longer and narrower than the shape it is afterward to be formed into and used, such piece of leather having a narrow exterior strip combined with inwardly-projecting tongues or projections, and in such a manner that the said tongues or 30 projections serve to drive the nails through, by means of which the skeleton tap or heel-piece is united to the solid sole or heel-layer, so as not to interfere with or obstruct the usual parts for sewing or pegging the sole or heel, rand 35 or welt. By the projections or tongues, as described, less labor and material are required to fill the middle portion of the skeleton sole or heel, as will hereinafter be more fully shown and described, reference being had to the accompanying drawings, in which—

Figure 1 represents a plan view of my improved slip-tap after being cut out by its die, and before being formed or molded. Fig. 2 represents a plan view of the same as formed and attached to a solid sole. Fig. 3 represents an edge view of Fig. 2. Fig. 4 represents a plan view of my improved heel after being cut, and before being formed and molded. Fig. 5 represents a plan view of the heel after being 45 formed and nailed to a layer of solid heel-piece. Fig. 6 represents an edge view of Fig.

5. Figs. 7, 8, and 9 represent modifications of my invention.

Similar letters refer to similar parts wherever they occur on the different parts of the 55 drawings.

In carrying out my invention I use a die, and by means of it I cut out a narrow strip of leather, A, with a cut-away portion, A', in its upper end, where the toe part of the sole or rear convex part of the heel is to be formed, so as to enable the improved heel or tap to be afterward readily curved and molded at this point. From the narrow strip A project inwardly the tongues or projections A" A", which 60 are made to interlock each other from opposite sides, so as to utilize the greatest amount of stock and to leave no waste material. The projections or tongues A" may be of various forms, as shown in Figs. 1, 4, 7, 8, and 9, 65 without departing from the spirit of my invention.

A", in Figs. 2, 3, 5, and 6, represents the solid-leather sole or heel-piece, to which I attach my improved skeleton sole, rand, welt, 70 or heel by means of nails b b, driven through the projections A" A", as shown, so as to be out of the way, and not to interfere with the usual pegging or sewing necessary to secure the sole and upper and heel to the boot or shoe. 75

After the skeleton tap or heel is cut out, as shown in Figs. 1, 4, 7, 8, and 9, it is spread out and moved endwise, so that its bottom edges, a' and a", come in a line, or nearly so, as represented in Figs. 2 and 5, such bottom 80 edges, a' a", being originally died out, one a little longer than the other, as shown in Figs. 1, 4, 7, 8, and 9. By so spreading out the skeleton tap or heel and moving its legs endwise, I am able to procure with ease the desired outer shape of the finished sole or heel, as shown. The upper convex portion, a, having the cut-away portion A', enables it to be readily 85 formed, expanded, and moved to the desired shape of the curvature at the toe of the finished sole or rear curvature of the heel, as represented, respectively, in Figs. 2 and 5.

After the skeleton tap or heel-blank is cut out by means of a proper die for the purpose, as described, it is soaked in water and molded 90 by means of proper molds to the required form of the heel, welt, sole, or rand, and after being 95

allowed to dry and set to its shape it is ready to be used in the manner described, and it will thus be seen that I produce a pieced or skeleton heel or tap which has an unbroken exterior edge without any joints, and I am thus

enabled to burnish and finish such exterior edge equally well as if it were a solid piece of leather.

The open space between the projections A" 10 in Figs. 2 and 5, I prefer to fill up with small pieces of leather or leather-board, or suitable filling material. By making the heel or tap blank with interlocking projections, as shown in Figs. 1, 4, 7, 8, and 9, I utilize the greatest 15 amount of the stock; but such projections may be made short enough so as to project by each other more or less or not to project by each other without departing from the essence of

my invention, the main feature of the invention being the unbroken continuous outer edge 20 and suitable nailing projections on the inner side, for the purpose set forth.

Having thus fully set forth the nature, construction, and operation of my invention, I wish to secure by Letters Patent, and claim— 25

As an improved article of manufacture, a skeleton tap or heel-lift, as described, having an exterior continuous edge and internal tongues or projections, as and for the purpose set forth. 30

In testimony whereof I have affixed my signature in presence of two witnesses.

GEORGE A. WHITE.
